UNITED STATES PATENT OFFICE.

JOHN CHITRA, OF CHICAGO, ILLINOIS.

PICTURE.

Application filed October 12, 1925. Serial No. 62,037.

My invention relates to a novel improvement in the art of making pictures and has special reference to an illuminated picture and the method of making same.

5 The object of my invention is to produce pictures which will have a pleasing appearance when illuminated by light thrown upon the outer surface thereof and will have even a more pleasing appearance when illuminated 10 from the back so that the pictures are seen by transmitted light.

A further object is to provide a method of producing pictures which will have pleasing appearances both by reflected and by 15 transmitted light.

The colors which I use in making my pictures are mainly what are known as aniline colors, and one important feature of my invention consists in the production of a peculiar 20 base material for receiving the colors or paints in the production of the pictures.

In order to obtain the peculiarly beautiful effect which I desire I have found that it is necessary to prepare a translucent base 25 with what I term a pebbly or roughened surface presenting many small surfaces arranged at many angles one to another.

I have found that one practical method of producing the desired pebbly or roughened 30 surface is to spray clear varnish upon a cloth of the proper kind. I have found that a fine grade of linen cloth is suitable for a base.

In preparing the base I apply the clear 35 varnish to both sides or surfaces of the cloth, the cloth having first been stretched and secured to a suitable frame. I apply the clear varnish by means of an air spray and of such a consistence or fluidity that 40 the exceedingly small drops of the varnish which are deposited upon the cloth retain, to some extent, their globular or rounded shape, particularly upon their outer surfaces, so that when the base is dried after the application 45 of the varnish it presents what I term a pebbly or roughened surface having many small surfaces which act to reflect light at many angles, and also which act as lenses to refract or turn the light in many directions.

After the varnish has been dried and

hardened I apply the colors, to produce the picture, to the varnished surfaces. I preferably apply the colors to the front surface of the base by means of an air brush, that is, 55 by spraying the colors upon the surface, and I use aniline colors for this purpose, using the necessary colors and tints to bring out the result desired. I then proceed to develop or bring out the deeper shadows or 60 darker parts of the picture by likewise spraying aniline colors upon the rear surface of the base.

The aniline colors do not give the contrast which is necessary to produce a picture for 65 reflected light, or what may be termed a daylight picture. For this purpose I apply oil colors to the high light portions of the picture, or to those parts which it is necessary or desirable to cause to stand out 70 more prominently. Having finished the application of the colors, as described, to produce the picture desired, I next apply a coat of clear varnish to the outer surface of the base over the whole surface thereof, and 75 when this coat of varnish has dried to a sticky or tacky condition I apply to the surface prepared clear glass particles in the form of very small globules, or what are known as "beads" or dust covering the surface completely and a layer of these glass particles adhere to the tacky varnish.

Having prepared the picture in the manner described, I mount it in a deep frame and arrange an incandescent electric lamp 85 behind the picture in a position to best illuminate same from the rear. Certain pictures for this purpose are usually selected because they present an appearance particularly adapted for especially bright illumination in one part and from which point the whole picture has the appearance of being illuminated, such, for instance, as sunlighted or moonlighted land or water scapes.

In the accompanying drawings I have illustrated the product and the method of producing the product.

Fig. 1, is a front view of a picture made in accordance with my invention;

Fig. 2, is a horizontal section on the line 100 2-2 of Fig. 1;

Fig. 3, is an enlarged fragmentary sec-

tion of the base or material upon which the picture is produced, showing the first step in the process and taken on the line 3—3 of Fig. 1;

5. Fig. 4, is a section similar to Fig. 3 and illustrating the next step after the application of the colors; and

Fig. 5, is a similar section after the application of the glass globules or beads.

10. In said drawings 1 is the linen or cloth base which is stretched upon an open frame 2, which in turn is adapted to be mounted in a relatively deep picture frame 3. Preferably, when finished, the frame 3 is closed 15 at the back by a closure board 4.

In the process hereinbefore described varnish is first sprayed upon both surfaces of the cloth. The varnish is indicated at 5 and has a pebbly or roughened outer surface,

20. The next step is the application of the colors which is indicated at 6 on the front and 7 on the back. That on the back being for the purpose of accentuating the shadows or deeper parts of the picture. These colors

25. are aniline colors. Then the high lights are brought out by the application of oil colors by hand to the parts necessary, as for instance, the red tile roofs, etc., and indicated at 8, Fig. 4. After the colors have been applied a coat of clear varnish 9 is applied to the front of the picture and when it has dried to a tacky or sticky condition small clear glass globules, or glass dust, is applied to the varnish and a layer of these fine glass 30 particles adheres to the varnish completely 35 covering same, as shown at 10.

After the picture is completed it is mounted in the frame 3 and an electric lamp 11 is arranged behind the picture in the place 40 which will best bring out the picture, as for instance, behind the representation of the sun, as shown at 12, in Fig. 1.

45. As many modifications of my invention will readily suggest themselves to one skilled in the art, I do not limit or confine my invention to the specific steps or order of steps, or to the specific product herein described and illustrated.

I claim:

50. 1. The method of making pictures which consists of spraying varnish upon a cloth base to produce a pebbly or roughened surface, applying translucent colors to said prepared surface to produce the picture desired, 55 applying varnish over the colors, allowing the varnish to dry until it becomes tacky and applying fine sand-like particles of glass to the varnish, while in tacky condition, whereby the picture is given a permanent 60 coating of said particles.

2. The method of making pictures which consists in applying varnish to a cloth base in such a manner as to provide a pebbly surface, applying aniline colors to the varnish 65 to produce the picture desired, applying oil

paints to the high lights of the picture, coating the picture with varnish and allowing it to dry until it becomes tacky, and while it is tacky applying transparent particles, such as glass, to provide a coating of such particles.

3. The method of making pictures which consists in applying clear varnish to both surfaces of a base consisting of a sheet of cloth, such as fine linen, applying translucent colors to one side of the base which is to be exposed to view to produce the general effect of the picture desired, applying similar colors to the opposite side to assist in producing the shadows or deeper parts of the picture, applying a coating of varnish to the exposed surface and permitting it to dry to a tacky condition and at such time applying a coating of relatively small transparent particles to the tacky varnish to provide a permanent coating of such particles.

4. The method of making pictures adapted to be illuminated either from the front or from the rear and which comprises, the application of a clear varnish to each surface of a base consisting of fine woven cloth, the application of translucent colors to the front surface to portray the picture desired, the application of similar colors to the rear surface to deepen the shadows of the picture, the application of oil colors to the front surface to heighten the high lights of the picture, coating the front surface with clear varnish, and when the varnish has dried sufficient to be tacky the application thereto of a coating of fine clear glass particles.

5. The article of manufacture herein described, comprising a picture painted with translucent paint upon a base which has first been coated with varnish in such a manner as to present a pebbly surface, and the exposed surface covered by a layer of fine glass particles secured by a coating of varnish applied over the paint.

6. The step in the herein described process of making translucent pictures, which consists in applying a clear varnish, to the surface of a picture foundation of fine woven cloth, in such a manner as to produce a pebbly surface when the varnish has dried.

7. The method of making pictures which consists in applying varnish to a cloth base in such a manner as to produce a pebbly surface thereon and applying paint to said pebbly surface to produce the picture desired.

8. The method of making pictures which consists in applying varnish to a cloth base in such a manner as to produce a pebbly surface, applying paints to said pebbly surface to produce the picture desired, and covering the paint coating with a coating of varnish.

9. A picture adapted to be illuminated from the rear and also to present a pleasing appearance when illuminated wholly from the front and comprising, a fine woven cloth

base coated front and back with varnish which presents a pebbly or rough outer surface, a picture portrayed on the exposed surface by aniline colors, the deeper parts or shadows brought out by aniline colors applied to the back, the high lights brought out by the application of oil colors to the exposed surface, the exposed surface coated with clear varnish over the paints, and a layer of small clear glass particles covering the exposed surface and secured by the last mentioned coat of varnish. 10

In testimony whereof, I have hereunto set my hand, this 7th day of October, 1925.

JOHN CHITRA.
